BIRD STATION

Thomas E. Brown, Slatersville, R.I., assignor to Rexall Drug and Chemical Company, Los Angeles, Calif., a corporation of Delaware

Filed July 6, 1965, Ser. No. 86,044

Term of patent 14 years

(Cl. D31—2)

FIG. 2

FIGURE 1 is a perspective view of a bird station showing my new design embodied in a bird feeder;

FIGURE 2 is a perspective view of a bird station showing my new design embodied in a bird house;

FIGURE 3 is a side view of the bird station; and,

FIGURE 4 is a cross-sectional view of the bird station taken at line 4-4 of FIGURE 1.

The dominant features of my design reside in the portions shown in full lines.

I claim:

The ornamental design for a bird station, substantially as shown and described.
